CLAIM

The ornamental design for an electronic cable, as shown and described.

DESCRIPTION

FIG. 1 is a perspective view of an electronic cable showing my design;

FIG. 2 is a right side view thereof;

FIG. 3 is a left side view thereof;

FIG. 4 is a front side view thereof;

FIG. 5 is a back side view thereof;

FIG. 6 is a top view thereof; and,

FIG. 7 is a bottom view thereof.

The broken lines shown in the drawings represent portions of the electronic cable that form no part of the claimed design.
